PRIMUS OTTO DORER, OF LEE, ENGLAND, ASSIGNOR TO S. SMITH & SON, LIMITED, OF WESTMINSTER, ENGLAND.

CENTRIFUGAL GOVERNOR AND SPEED-INDICATOR.

1,073,031.

Specification of Letters Patent.

Patented Sept. 9, 1913.

Application filed September 7, 1912. Serial No. 719,220.

To all whom it may concern:

Be it known that I, PRIMUS OTTO DORER, a subject of the King of England, residing at Lee, in the county of Kent, England, 5 have invented certain new and useful Improvements in Centrifugal Governors and Speed-Indicators, of which the following is a specification.

This invention relates to centrifugal governors, speed indicators and the like, the object being to provide mechanism which shall be superior to those hitherto employed as regards uniformity and accuracy of action.

Hitherto, in some centrifugally-operated mechanisms a weighted governor arm has been connected with a sleeve, or with some other movable member, by means of a link, with the result that, as the governor arm 10 moved outward under the centrifugal action, the angularity of the link with reference to the arm, or to the movable member, or with reference to both, varied in such a way that the amount of movement imparted 15 to the said member for a given change of speed of the revolving element at low speeds was greater than that imparted for the same change of speed of the revolving element at higher speeds. In other constructions cams have been employed to correlate 20 in various desired manners, the movements of the governor arms themselves. Such cams have commonly been employed in pairs 25 symmetrically spaced in order to produce symmetry in the resulting forces, but where the space available is small, the employment of cams in duplicate cannot be followed. I have further discovered that yet another cause of irregularity, where the forces acting 30 upon the movable member are not symmetrically applied or are unbalanced for any reason, arises from the production, in these circumstances, of a force tending to bind the said movable member frictionally upon its 35 guide or mounting. Irregularity was further introduced by the fact that if the governor arm when in its position of rest is approximately parallel to the governor spindle, it is moved outward very considerably 40 without being appreciably lifted, while the converse holds good at the other limit of its possible movement.

According to this invention, there is employed in a speed indicator or like centrif-

ugal mechanism, in conjunction with a governor arm or other centrifugal mass, a single hook-like cam rigidly supported upon a member to be moved by the said centrifugal mass and maintained in direct engagement with the said governor arm or other centrifugal mass, with or without an anti-friction bowl for the cam; the cam may be maintained in direct engagement conveniently by means of a spring. I have found that with the construction in which the cam is in the 60 form of a hook-like member, as just hereinbefore referred to, the member carrying it is liable to be subjected to a force tending to bind it frictionally upon its guide or mounting, and this frictional binding is inimical 65 to responsiveness of action. This I have found to be the case notably in connection with speed indicators such as are employed on self-propelled vehicles. The said binding effect prevents a change in position of 70 the member subjected to it until the change in speed has become sufficiently great to allow the operating force to more than overcome the binding effect. In order to deal 75 with this, I introduce a force to counteract the said binding effect, for example, by suitably inclining the cam-face to the direction 80 of movement of the said member, so that the cam serves to apply both such a counteracting force and an operating force. 85

In the accompanying drawings:—Figure 1 is an elevation in part section of a centrifugal governor device according to this invention as applied to a speed indicator, and Fig. 2 is an elevation at right angles to Fig. 1.

Like letters indicate like parts in both the figures.

Upon the spindle A is carried a ring B which constitutes the centrifugally-operated 95 element. A support for the ring is provided by two pivots disposed across the diameter of the ring, the pivots being shown at C and being carried by a cap or bell-like sleeve C' rigidly connected to the spindle 100 A. A sleeve D is mounted upon the spindle and is provided with a hook E rigidly secured to it, and which engages a pin F provided with an anti-friction roller F' mounted in the ring B. Between the sleeve D and the bell-shaped sleeve C' is a controlling 105 spring G in compression. The sleeve D carries a rack D', and is cut away as shown at

D² in order to balance the centrifugal action of the hook E which is mounted on that side of the sleeve. The spindle is driven by a pinion H, and the rack D' engages a pinion J connected to the speed indicator pointer in any well known way.

The operation of the device is as follows:—When the spindle is revolved centrifugal forces tend to make the ring B assume a horizontal position, such as is indicated in chain line in Fig. 1. As the ring moves from the position of rest shown in full line, it carries with it the hook E, so displacing the sleeve D against the controlling force of the spring G, finally taking up some position intermediate between the position of rest and that shown in chain line. The condition of the sleeve D under the action of the force applied to the hook E and that exerted by the spring G, is one in which it is tilted, or tends to be tilted, owing to the want of lateral symmetry arising from the fact that only one hook is employed. The result of this is that frictional binding between the sleeve and the spindle tends to be produced, and would be unchecked if the cam-face E' of the hook were at right angles to the spindle, and would be enhanced if the face E' were upwardly sloped. By giving to the face E', however, a slight downward (as viewed in Fig. 1) slope, a force is introduced, by the action thereon of the pin F, which counteracts more or less completely the said tilting action, so reducing or eliminating the consequent binding effect. The reduction or removal of the binding effect has for its result a greater responsiveness in the indications of the instrument, that is to say, there is a less change of speed necessary to produce some movement of the sleeve D, since the latter is no longer held by the same frictional binding force, and does not therefore require the same force to be exerted before it will move. The cam-face of the hook may further be shaped, apart from being inclined to the spindle, in any way that may be necessary to produce a desired arrangement of the scale. For example, it may be convenient to have the very early indications of an instrument intended for use on a motor-car up to, say, twelve miles an hour, somewhat crowded on the scale, while those from twelve to thirty-five may be more openly spaced, and those above thirty-five be again somewhat closely spaced; any desired arrangement of spacing may be ob-

tained by suitably shaping the cam-face of the hook.

It is preferred to arrange that the weight- 60 ed arm or arms, or, in the construction illustrated, the plane of the ring B, shall be somewhat inclined to the axis of the spindle, and that the upward movement shall be limited to that in which the inclination 65 reaches, say, 45°, as a maximum, in order that the hereinbefore referred to irregularity of scale may be reduced to some extent, apart from the reduction effected by specially shaping the cam-face. 70

What I claim as my invention and desire to secure by Letters Patent is:—

1. In a centrifugal governor, the combination of a rotatable shaft; a ring surrounding and pivotally mounted on the shaft; a 75 sleeve slidably mounted on the shaft; a hook carried by the sleeve and engaging with said ring and adapted to be moved thereby; and a spring mounted on the shaft engaging with and holding said sleeve under tension, 80 substantially as described.

2. In a centrifugal governor, the combination of a rotatable shaft; a ring surrounding and pivotally mounted on the shaft; a roller journaled on said ring; a sleeve slidably mounted on the shaft; a hook carried by said sleeve and having an inclined portion engaging with said roller, said ring adapted to move the sleeve through said roller and hook engagement; and a spring 90 mounted on the shaft engaging with and holding said sleeve under tension, substantially as described. 85

3. In a centrifugal governor, the combination of a rotatable shaft; a sleeve fixedly 95 mounted on said shaft; a ring surrounding and pivotally mounted on said sleeve; a sleeve slidably mounted on the shaft; a hook carried by said sleeve and having an inclined portion engaging with said ring, said ring 100 adapted to move the slideable sleeve through said hook engagement; and a spring mounted on the shaft and having its respective ends engaging with said fixed and movable sleeves and adapted to hold the latter under 105 tension, substantially as described.

In testimony whereof I have signed my name to this specification in the presence of two subscribing witnesses.

PRIMUS OTTO DORER.
